REMOVABLE BOTTLE CAP

Bertram C. Tate, Brooklyn, N. Y.

Application November 15, 1943, Serial No. 510,343

1 Claim. (Cl. 215—46)

The invention relates to bottle caps, and more especially quick removable bottle caps.

The primary object of the invention is the provision of a cap of this character, wherein the same is so constructed that it can be removed without the use of a special tool or the usual bottle cap opener, the said cap being detached by finger engagement therewith.

Another object of the invention is the provision of a cap of this character, wherein the same is clinched upon the mouth head of the bottle to be securely held upon the latter, and for sealing the contents of the same, the peripheral flange of this cap being sectioned and doubled on itself, so that by finger pressure upon any of the sections the said cap can be easily and quickly removed from the bottle.

A further object of the invention is the provision of a cap of this character, wherein the clinching of the same to the bottle is had by indentations, these reinforcing the flange of the cap in addition to securing the cap in place on the bottle, the flange being cut into to effect releasing tabs or lips for the quick removal of the cap from the bottle, without the use of an instrument for so doing.

A still further object of the invention is the provision of a cap of this character, which is simple in construction, thoroughly reliable and efficient in its purpose, strong, durable, and inexpensive to manufacture and install.

With these and other objects in view the invention consists in the features of construction, combination and arrangement of parts as will be hereinafter more fully described, illustrated in the accompanying drawing, which shows the preferred form, and pointed out in the claim hereunto appended.

In the accompanying drawing:

Figure 1 is a top plan view partly in section of the cap constructed in accordance with the invention.

Figure 2 is a side view thereof.

Figure 3 is a sectional view on the line 3—3 of Figure 1.

Figure 4 is a sectional view on the line 4—4 of Figure 1.

Figure 5 is a sectional view on the line 5—5 of Figure 1.

Figure 6 is a bottom plan view of the cap.

Figure 7 is a fragmentary detail view.

Figure 8 is a view similar to Figure 7 showing one of the indentations opened.

Similar reference characters indicate corresponding parts throughout the several views in the drawing.

Referring to the drawing in detail A designates generally a portion of the neck of a bottle having at the open mouth end 10 thereof an external an-

nular bead 11 as usual for the fastening of a cap generally denoted at B thereto, and constructed in accordance with the invention as hereinafter set forth.

5 The cap B comprises a circular metal crown 12, although the material may be other than metal having inherent springy character, formed with a corrugated flared skirt 13 providing vertical outtruck ribs 14 and instruck indentations 15, alternating therewith, the latter being for the crimping or clinching of the skirt 13 to the bead 11 on the mouth end 10 of the neck A of a bottle. The ribs 14 are vertically slotted at 16 in the lower portions thereof, and next to an outturned flange 17 concentric to the skirt and unitary therewith, the flange 17 being turned upwardly and inwardly on itself throughout the extent thereof to provide an outwardly inclined overhanging lip 18 with relation to the said flange 17. This lip 18 has notches 19 therein registering with the ribs 14 for the interfitting of the latter therein. The flange 17 and lip 18 are radially slotted at 20, these being diametrically opposed to each other at four points circumferentially of the crown 12 and the inner ends of these slots 20 terminate within the indentations 15 next thereto, so as to provide independent finger releasing tabs 21 about the said crown 12, to permit the easy and quick release of the cap from the bottle by hand pressure upon a selected tab 21.

When an upward pressure is exerted upon a selected tab 21 the cap B becomes loose upon the bottle and such cap by further upward pull by hand thereon is removed from the said bottle.

35 The lip 18 fulcrums on the ribs 14 when an upwardly directed force is applied to a tab 21, and thereby releasing the crimping engagement of the cap with the bottle mouth end 10. The slits 16 in the ribs 14 open during the upward pressure upon the flange 17 for the freeing of the cap from the bottle, these slits 16 being normally closed.

What is claimed is:

45 A bottle cap comprising a crown portion having a flared skirt providing alternating ribs and indentations when crimped upon a bottle mouth, the ribs having their lower portions vertically slotted, a radially slotted flange extending outwardly from the lower edge of the skirt, and a radially slotted lip overlying the flange and extending inwardly and upwardly from its periphery, the inner edge of the lip having recesses receiving the ribs, and the inner edge of the lip being adapted to contact with the ribs when upper pressure is applied to the flange whereby to provide a fulcrum on which the flange moves to release the skirt from the bottle.
